UNITED STATES PATENT OFFICE.

LEE C. SHARP, OF PLATTSMOUTH, NEBRASKA, ASSIGNOR TO FRANZ BRÜCKMANN, JR.,
OF BRUNSWICK, GERMANY.

MANDREL FOR SHEET-METAL WORKING.

1,025,318.

Specification of Letters Patent.

Patented May 7, 1912.

Application filed March 8, 1907, Serial No. 361,310. Renewed October 2, 1911. Serial No. 652,414.

To all whom it may concern:

Be it known that I, LEE C. SHARP, of the city of Plattsouth, in the county of Cass and State of Nebraska, have invented certain new and useful Improvements in Mandrels for Sheet-Metal Working, of which the following is a full, clear, and exact specification, such as will enable others skilled in the art to which it appertains to 10 make and use the same.

My invention relates particularly to a mandrel for forming and holding can body blanks in position for seaming them.

It is especially adapted to the formation 15 of lap seams, that is to say, in which one edge of the blank is lapped over the other to form the seam which is subsequently soldered to render it permanent. Heretofore devices of this sort have been composed 20 of a horn or mandrel around which the blank tin is folded and held by wings or other devices engaging the tin.

The object of my invention is to dispense 25 with these devices for engaging the tin to hold it on the horn.

A further object of my invention is to provide means for holding the lap parts of the body at the seam firmly together so that the engagement of the edges during the 30 soldering operation will not depend upon the pressure of the soldering tool, thus enabling me to join together the two edges of the body blank and secure them by the fusing of the tin with which the metal plate is 35 coated.

I attain these objects by magnetic action which may be through the mandrel itself, or a part in connection therewith. The magnet is preferably of the electromagnetic 40 type, although my invention is not so limited.

My invention involves various other features of major or minor importance, and all will be fully set forth hereinafter and particularly described in the claims.

Reference is had to the accompanying drawings which illustrate, as examples various types of the invention, in which drawings—

Figure 1 is a sectional view of one form of the mandrel; Fig. 2 is a sectional view of a second form; and Fig. 3 is a sectional view of a third form.

In Fig. 1, the mandrel is composed of two 55 approximately semi-cylindrical sections *a*

which form the poles of the magnet and are joined by a magnet core *b* around which the winding *c* is placed. The can body blank indicated at *d* is folded either manually or by machinery over the mandrel or horn, and its edges lapped as indicated at *d'* to form the lap seam. Upon energizing the coil *c* the blank will be attracted to the mandrel at the points indicated by the arrows in Fig. 1, and the magnetic force may be made 60 sufficiently great to hold the sheet metal plate in position as firmly as will be desired under any condition. It will be observed that the force holding the blank is exerted from the interior of the mandrel as contrasted 70 distinguished from the exterior thereof, thus leaving the outer side of the can body entirely free and unobstructed particularly at the seam, without, however, in any way affecting the force which may be exerted to 75 hold the edges of the blank firmly lapped against each other. This allows the soldering operation to be carried on without restraint and when the can is to be removed from the mandrel the coil *c* may be deenergized 80 and the can withdrawn easily. In sealing the seam by fusing the tin with which the metal plate is coated, my invention becomes peculiarly useful. It is a fact that commercial tin plate composed of sheet 85 steel coated with tin furnishes sufficient tin to solder the lap seam. However, it has been heretofore impossible to solder the seam in this manner owing to the fact that great pressure must be applied to the overlapped 90 parts during the fusing operation, otherwise the parts will warp and the hermetic joint be prevented. By means of my magnetic mandrel, however, the lapped parts of the seam are held firmly against each other by 95 pressure which may be as great as necessary and the heating operation necessary to fuse the tin and form the joint may be carried on unrestrained. The magnetic force may be continued on the seam until the tin cools 100 and sets, and the seam is then complete.

Fig. 2 shows a modification in which the mandrel is adapted to be provided with a number of longitudinally disposed windings of which one is indicated at *c'*. Similar 105 windings are arranged in all of the cavities around the entire circumference of the mandrel with the result that upon energization of the windings the blank *d* is held firmly at all points.

Fig. 3 shows a form which is rectangular in cross section, adapted for the formation of square cans in which the parts a' , b' , and c' correspond to the parts a , b and c of Fig. 1, and perform precisely the same functions.

It is also pointed out in connection with this invention that the mandrel may be made of any length desired, thus enabling a can of any length to be constructed and 10 indeed adapting the invention to the formation of various other tubular sheet metal articles of indefinite length.

Having thus described the preferred embodiment of my invention, what I claim as 15 new and desire to secure by Letters Patent of the United States is:—

1. A horn or mandrel adapted to support the blanks of sheet metal cans and having cross-sectional shape corresponding to that of the can, said horn or mandrel being provided with electro-magnetic means acting upon the inner surface of the blank to hold the blank in position around the mandrel leaving the outer surface of the blank un- 20 obstructed.

2. A horn or mandrel adapted to have the blanks of sheet metal cans formed around it,

the horn or mandrel having a cross-sectional shape corresponding to that of the can and an electromagnetic means embodied within the horn or mandrel as a part thereof, whereby said blank may be held around the mandrel in position for soldering, leaving the outer part of the blank unobstructed during the soldering operation. 30 35

3. A horn or mandrel for forming the sheet metal cans comprising two sections forming the poles of a magnet and spaced from each other, said sections forming to the cross-sectional shape of the can, a magnet core joining the said sections together and an electric magnet winding around the core, whereby the blank of the sheet metal can is held around the mandrel by electromagnetic force exerted from the interior 40 thereof and the outer portion of the blank is left unobstructed during the soldering operation. 45

In testimony whereof I have hereto put my hand this 15th day of February, 1907. 50
